BUILDING PANEL OR THE LIKE

Truman L. Newberry, Jr., 6817 Candlewood Drive,
Raleigh, N.C., and Samuel B. Ashford, 2671 Davis St.,
Raleigh, N.C. 27608

Filed Sept. 8, 1970, Ser. No. 24,872

Term of patent 14 years

Int. Cl. D25—01

U.S. Cl. D13—1 J

FIG. 1

FIG. 2

FIG. 3

FIG. 1 is an elevational view of the building panel or the like;

FIG. 2 is an enlarged view of such panel; and

FIG. 3 is a slightly modified pattern showing the same. The building panel or the like is of conventional thickness with the rear being essentially plain and unornamented.

We claim:

The ornamental design for a building panel or the like, as shown and described.
